UNITED STATES PATENT OFFICE

MAURICE ALLAND, OF ATLANTIC CITY, NEW JERSEY

RAZOR

Application filed January 20, 1930. Serial No. 421,961.

The object of the invention is to provide improvements in safety razors, and comprises improvements over U. S. Patent No. 1,624,707, issued April 12, 1927 to the applicant.

5 The razor illustrated and described in said patent, while very satisfactory and marking an advance over the prior art, presented a construction which necessitated that the operator grip the opposite end surfaces of the 10 blade-supporting head with the fingers of one hand, thus preventing the blade-retaining means from opening freely, while using the fingers of the other hand to rotate the handle in order to loosen the blade-retaining means 15 and release the blade.

An object is therefore to provide the blade-supporting head with an integral extension forming a portion of the handle, so that instead of having to grip the ends of said head 20 in loosening the same, and thereby affecting the otherwise free movement of said blade-retaining means, said extension is gripped by the fingers of one hand, while the fingers of the other hand grip and rotate the other portion 25 of the handle with respect to said first portion, in order to accomplish the same result as previously.

With these objects in mind the invention comprises further details of construction 30 which are hereinafter fully brought out in the following description, when read in conjunction with the accompanying drawings, in which Fig. 1 is a front elevation of one embodiment of the invention; Fig. 2 is a similar 35 view with the upper portion in fragmentary section and the blade-retaining means indicated in raised position by dot-and-dash lines; Fig. 3 is an end elevation; and Fig. 4 is a top plan view, partly in section. Fig. 5 is a plan 40 view of the type of blade used.

Referring to the drawings, the improved 45 razor holder comprises a handle formed in two sections 1 and 2, the first section being preferably hollow for the sake of lightness in weight and provided with a knurled portion 3, while said second section is provided with a knurled surface 2^a (disposed outwardly of the periphery of handle section 1 so that the latter will remain free for rotation 50 when said surface 2^a is gripped) and with an

axial bore 4, which opens at its free end into an enlarged recess 5, adapted to receive the adjacent end portion of said first handle section from which projects a unitary extension 6, said extension projecting through the bore 4 and terminating in a threaded end portion 7, and comprising a pin secured in any suitable manner in the end of said first handle section.

55 Integrally connected with the handle section 2 is a transversely extending, blade-supporting portion 8, having a recess 9 coaxial with the bore 4 upon the side opposite to said handle, to receive a flange 10 formed on the threaded end 7, but adapted to permit 60 relative movement between said blade-supporting portion and said first handle section 1. The upper surface of the blade-supporting portion is provided with lugs 11 positioned upon the opposite sides of the threaded end 7 of the handle, and at one end is provided with a lug 12 which cooperates with lugs 13 upon a blade-secur ing member 14 to form a hinge, said member being provided 70 with holes or recesses 15 to receive the free ends of the lugs 11, when a blade 16 rests upon the supporting portion 8 and is secured 75 in place by said member when in its operative or clamping position.

80 From the opposite sides of each end of said blade-supporting portion there extend integral arms 16^a, while between arms on the same side there extends a rod surrounded by alternately positioned rollers 17 and intermediate spacing washers 18, which cooperate 85 to serve as a guard for the adjacent edge of the blade 16, the tension upon said blade to curve the same being varied by rotating the handle section 1 to cause its threaded end 7 to engage to a greater or less degree the 90 blade-retaining member 14.

95 In the operation of this improved razor, and with the retaining means in raised position, a blade is placed upon the supporting portion 8 with the lugs 11 and threaded handle end extending through the blade. The retaining means is then lowered until it is caught by said handle end, which latter is then rotated by gripping the knurled surface 2^a with the fingers of one hand and rotating 100

- the knurled portion 3 of the handle section 1 with the fingers of the other hand, relative rotation being stopped when the desired tension is obtained upon the blade. To release 5 said blade this procedure is reversed, it being clearly understood that the fingers of neither hand need come into contact with any portion of the blade when the latter is being either tightened or loosened.
- 10 Having thus described my invention, what I claim and desire to protect by Letters Patent of the United States is:—
1. In a razor, a blade-supporting portion having a normally depending bored extension constituting a handle section, means pivoted to said portion to secure a blade thereon and provided with a screw-threaded aperture, a second handle section in line with and rotatable with respect to said first section, said second handle section having a part journaled in the bore of said extension and having a screw-threaded terminal normally engaged with the screw threads in said aperture, said extension adjacent its lower end having a finger-gripping portion extending outwardly beyond the second handle section, whereby the latter will remain free for rotation by fingers of one hand while the first section is held by fingers of the other hand, and means to prevent longitudinal movement of said second handle section whereby the pivoted cap may be removed to and from the blades supporting portion.
  2. In a razor, a blade-supporting portion having a normally depending bored extension constituting a handle section, means pivoted to said portion to secure a blade thereon and provided with a screw-threaded aperture, said pivoted means being curved transversely, said blade supporting portion being shaped in a manner complementary to said pivoted means whereby a blade may be flexed and held in position between said pivoted means and blade-supporting portion for shaving, a second handle section in line with and rotatable with respect to said first section, said second handle section having a part journaled in the bore of said extension and having a screw-threaded terminal normally engaged with the screw threads in said aperture, said extension adjacent its lower end having a finger-gripping portion extending outwardly beyond the second handle section, whereby the latter will remain free for rotation by fingers of one hand while the first section is held by fingers of the other hand, operating to permit the tension of the blade, having recessed ends to receive the pivoted member and upon the release of the clamping member to forcibly oscillate said member outwardly and thereby release the blade.
  3. In a razor, a blade-supporting portion having a normally depending bored extension constituting a handle section, means pivoted to said portion to secure a blade

thereon and provided with a screw-threaded aperture, said pivoted means being concaved transversely on its inner side, said blade supporting portion having an elevated central zone to cooperate with the concaved side to grip a blade and flex it to position for shaving, a second handle section in line with and rotatable with respect to said first section, said second handle section having a part journaled in the bore of said extension and having a screw-threaded terminal normally engaged with the screw threads in said aperture, said extension adjacent its lower end having a finger-gripping portion extending outwardly beyond the second handle section, whereby the latter will remain free for rotation by fingers of one hand while the first section is held by fingers of the other hand, operating to permit the tension of the blade upon the release of the clamping member to forcibly oscillate said member outwardly and thereby release the blade.

4. In a razor, a blade-supporting portion having a normally depending bored extension constituting a handle section, means pivoted to said portion to secure a blade thereon and provided with a screw-threaded aperture, said pivoted means being curved transversely, said blade supporting portion being shaped in a manner complementary to said pivoted means whereby a blade may be flexed and held in position between said pivoted means and blade-supporting portion for shaving, a second handle section in line with and rotatable with respect to said first section, said second handle section having a part journaled in the bore of said extension and having a screw-threaded terminal normally engaged with the screw threads in said aperture, said extension adjacent its lower end having a finger-gripping portion extending outwardly beyond the second handle section, whereby the latter will remain free for rotation by fingers of one hand while the first section is held by fingers of the other hand, operating to permit the tension of the blade, having recessed ends to receive the pivoted member and upon the release of the clamping member to forcibly oscillate said member outwardly and thereby release the blade.

In testimony whereof I have affixed my signature.

MAURICE ALLAND.
